UNITED STATES PATENT OFFICE.

ALBERTUS TRAVIS, OF JOHNSTOWN, NEW YORK.

FLESHING-MACHINE.

1,239,748.

Specification of Letters Patent. Patented Sept. 11, 1917.

Application filed November 23, 1916. Serial No. 133,069.

To all whom it may concern:

Be it known that I, ALBERTUS TRAVIS, a citizen of the United States, residing at Johnstown, in the county of Fulton and 5 State of New York, have invented a new and useful Flesching-Machine, of which the following is a specification.

This invention relates to flesching machines and is more particularly an improvement 10 upon the structure disclosed in an application filed by me on May 24, 1916, Serial No. 99,623.

One of the objects of the invention is to provide a grinding mechanism of improved 15 construction for use in connection with a flesching cylinder and which mechanism enables the operator quickly to reverse the drive so that the sharpening block will be shifted in one direction or another or be 20 entirely disconnected from its operating means.

Another object is to provide means whereby the lower feed roller of the mechanism is set in motion before it reaches the 25 limit of its movement toward the flesching cylinder, thus increasing the efficiency of the machine.

A further object is to improve upon the 30 construction of the means employed for shifting said roller.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without 40 departing from the spirit of the invention.

In the accompanying drawings the preferred form of the invention has been shown.

In said drawings:

45 Fig. 1 is a front elevation of the machine, a portion thereof being broken away.

Fig. 2 is a side elevation of the power transmitting mechanism controlling the operation of the grinder.

50 Fig. 3 is a side elevation of a portion of the machine.

Fig. 4 is a section on line 4—4 Fig. 1.

Fig. 5 is a section through the means employed for transmitting motion to the yield- 55 able feed roller.

Fig. 6 is a detail view of the adjusting mechanism of the resilient roller.

Fig. 7 is an enlarged inner elevation of the clutch.

Fig. 8 is a section on line 8—8 Fig. 7. 30 Referring to the figures by characters of reference 1 designates a supporting frame having side portions 2 extending upwardly therefrom. In these side portions are journaled trunnions 3 extending from the ends 65 of a flesching cylinder 4 having oppositely pitched scraping blades 4' spirally arranged and meeting midway between the ends of the cylinder, as shown. Arranged on one of these trunnions is a pulley 5 adapted to 70 transmit motion through a belt 6 to a pulley 9 mounted for rotation on a fixed shaft 10. A small pulley 11 rotates with the pulley 9 and is adapted to transmit motion through a belt 12 to a large pulley 13 supported by a 75 transverse shaft 14 extending throughout the width of the machine. A link 15 couples the two shafts 10 and 14 as shown.

Extending inwardly from the pulley 13 is a hub 16 containing clutch mechanism such 80 as shown in detail in Figs. 7 and 8. By referring to these figures it will be noted that the hub has a recess 19' the wall of which is toothed as at 20'. Secured to the shaft 14 so as to work within the recess 19' is an arm 85 21' to which a pawl 22' is pivotally connected, this pawl being normally pressed outwardly against the toothed wall of recess 19' by a spring 23'. An arm 25' extends from the frame of the machine and has a 90 laterally extending finger 26' which constitutes a guide for a clutch member 27'. This clutch member is slidably mounted on but does not rotate with the shaft 14. The clutch member includes oppositely extending arms 28' one of which is forked as at 29' and slidably engages the finger 26'. Pins 30' project from the respective arms 28' and extend into the recess 19' where they will be 95 successively engaged by the pawl 22' during the rotation of shaft 14. A yoke 31' engages the clutch member 27' and is arranged at the upper end of the lever 17. The foot lever 17 is normally in raised position and, consequently, the pins 30' are normally 100 pressed into the recess 19' where one of them will be engaged by the pawl 22' thus holding said pawl disengaged from the teeth 20' and allowing the pulley 16 to rotate freely on the shaft 14. Thus it will be seen that by 110

momentarily depressing the lever 17, the pins 30' will be withdrawn from the recess 19', thus allowing pawl 22' to spring outwardly into engagement with one of the teeth 20'. Consequently the rotating pulley 16 will also transmit motion through pawl 22' and arm 21' to the shaft 14 and cause said shaft to rotate. Upon the completion of a one half revolution, the pawl 22' will come into contact with the other pin 30' which has moved back into the recess 19' as soon as the foot lever has been released, and, consequently, the pawl will be disengaged from the tooth 20' so that the rotation of the shaft 14 will cease while the pulley 18 will continue to rotate. In other words, each time the foot lever is depressed, the shaft 14 is given one complete rotation with the pulley 13 and then stopped.

20 A sprocket 18 is carried by the hub 16 and is engaged by a chain 19 which serves to transmit motion through a sprocket 20 secured to one end of a shaft 21 on which is arranged a corrugated feed roller 22. Shaft 21 is mounted within spring pressed bearings 23 so as to be capable of yielding upwardly when necessary.

25 Shaft 14 has spaced cams 24 secured thereon, each cam being slightly flattened on its periphery at the point farthest removed from the shaft 14, this flattened portion normally bearing on an anti-friction roller 25 carried by a finger 26 which is pivotally connected, as at 27, to one arm 28 of a bell crank lever 29. The other arm of this bell crank lever has a bearing 30 slidably mounted thereon and in this bearing is journaled the shaft 31 of a yieldable feed roller 32 preferably of rubber and which is normally disposed directly under the feed roller 22. A lug 33 extends downwardly from the bearing into an elongated recess 34 and this lug is engaged slidably by a stem 35 having a threaded end engaging one end wall of the recess 34, as shown at 36. This stem has a collar 37 against which the lug 33 bears and said lug is held against the collar by a spring 38 which engages an adjusting nut 39 threaded into one wall of the recess 34. Said nut has a head 40 by means of which it can be rotated readily, and the stem 35 also has a head 41 to facilitate the rotation thereof.

55 Extending transversely of the machine in front of the fleshing cylinder 4 is a guide beam 40' having longitudinal flanges 41' along the upper edge thereof slidably engaged by a carriage 42. On this carriage is 60 adjustably mounted a block 43 carrying a sharpening element 44 which can be in the form of a block of carborundum or the like. A screw 45 is employed for adjusting the blocks 43 and 44 toward or from the fleshing cylinder without correspondingly moving

the carriage 42. Depending from the carriage is a tongue 46 through which extends a guide rod 47 and a feed screw 48. The guide rod and feed screw are parallel and extend throughout the width of the machine. The feed screw is provided at one end with a gear 49 and another gear 50 is arranged in the same plane therewith on the trunnion 3 of the fleshing cylinder. Pivotally mounted on the screw 48 is an arm 51 preferably substantially L-shape and on this arm are journaled intermediate gears 52 and 53 which are constantly in mesh with each other. The gear 52 is constantly in mesh with the gear 49, but the gear 53 is only in mesh with gear 50 when arm 51 is moved downwardly to one limit of its movement. When the parts are thus located gear 52 is out of mesh with gear 50. By slightly raising the arm 51 gear 53 can be shifted out of mesh with the gear 50 and gear 52 will remain out of mesh with gear 50. By further raising the arm 51, however, gear 53 will remain out of mesh with gear 50, while gear 52 will move into mesh with gear 50. Thus it will be seen that when arm 51 is at one limit of its movement, motion will be transmitted in one direction from gear 50 to the gear 49 and, when the arm 51 is at its other limit of movement, the operation of the gear 49 will be reversed. When arm 51 is in its intermediate position, motion will not be transmitted to the gear 49.

50 The rod 47 not only constitutes a guide for the tongue 46, but also serves as a means for actuating the arm 51. This rod is provided at one end with a radial arm 54 connected by a link 55 to the upper end of the arm 51. Thus by rocking the rod 47, arm 51 can be shifted to any one of the positions mentioned and the operation of the feed screw 48 controlled.

55 Secured to the shaft 21 at one end is a head 56 on which is slidably mounted a cylindrical extension 57 projecting from a conical friction disk 58. A spring 59 is mounted on the shaft 21 and within the extension 57, this spring bearing at one end against the head 56 and at its other end against the disk 58. The shaft 31 is provided on one end portion with a friction disk 60 and the parts are so proportioned that when shaft 31 is swung upwardly and forwardly the disk 60 will be brought into engagement with the friction disk 58 so that motion will be transmitted from shaft 21 to shaft 31.

In order that the rollers 25 on the fingers 26 may be held yieldingly in contact with the cams 24, brackets 61 are formed integral with the arms 28 of the bell crank lever and carry springs 62. Each spring is seated in a recess 63 and bears upwardly against the finger 26 thereabove.

60 Motion is preferably transmitted to the

machine by belts or the like operating a pulley 56' secured to one of the trunnions 3 of the fleshing cylinder. Motion will be transmitted from the pulley 5 to pulley 9 and thence from pulley 11 to pulley 13. Motion will be transmitted from the sprocket 18 to sprocket 20 and thence to the shaft 21. Each time the arms 28 are rocked by the cams 24, the feed roller 32 will move downwardly away from the fleshing cylinder 4, thus bringing the friction disk 60 out of mesh with the friction disk 58, after which the roller 32 will swing upwardly back to its normal position, bringing the two disks 58 and 60 again into engagement with each other and causing the two rollers 22 and 32 to rotate. When sharpening of the blades on the fleshing cylinder is desired, the rod 47 is rocked by means of a handle 57', thus to shift one or the other of the gears 52 and 53 into mesh with gear 50. Consequently, the feed screw 48 will be actuated and will cause the carriage 42 to shift longitudinally along the beam 40, thereby dragging the sharpening element 44 along the edges of the blades on the fleshing cylinder.

By providing the sliding bearing 30 for the shaft 31 the roll 32 can be adjusted readily toward or from the fleshing cylinder. The spring tension 38 is employed to automatically adjust the roll to a thick or thin skin.

For the purpose of yieldingly supporting each arm 28 and the parts carried thereby, a hanger 64 is suspended under each arm 28 from a cross bar 65. In this hanger is slidably mounted a head 66 which bears upwardly against the arm 28 and has a stem 67 surrounded by a spring 68. This spring 35 bears upwardly against the head and engages the hanger so as to yieldingly support the head and the arm 28 engaging the same. Obviously the downward swinging movement of the arm will be resisted by the 40 yieldingly supported head 66.

What is claimed is:—

1. In a fleshing machine, the combination with a fleshing cylinder mounted for rotation and a corrugated feed roller yieldingly supported adjacent thereto, of a spring 50 pressed friction disk revoluble with said roller, arms mounted to swing toward and from the feed roller and fleshing cylinder, a shaft journaled in the arms, a resilient feed

roller revoluble with the shaft, a friction 55 disk carried by said shaft and movable with the arms into and out of contact with the spring pressed friction disk.

2. In a fleshing machine, the combination with a fleshing cylinder mounted for rotation and a corrugated feed roller yieldingly supported adjacent thereto, of a spring 60 pressed friction disk revoluble with said roller, arms mounted to swing toward and from the feed roller and fleshing cylinder, a shaft journaled in the arms, a resilient feed roller revoluble with the shaft, a friction disk carried by said shaft and movable with the arms into and out of contact with the spring pressed friction disk, and means carried by the arms for shifting the resilient roller toward or from the fleshing cylinder.

3. In a fleshing machine, the combination with a fleshing cylinder mounted for rotation and a corrugated feed roller yieldingly 75 supported adjacent thereto, of a spring 70 pressed friction disk revoluble with said roller, arms mounted to swing toward and from the feed roller and fleshing cylinder, a shaft journaled in the arms, a resilient feed 80 roller revoluble with the shaft, a friction disk carried by said shaft and movable with the arms into and out of contact with the spring pressed friction disk, actuating cams 85 contacting with the arms, means for rotating the cams, and means for yieldingly holding the arms in contact with the cams.

4. In a fleshing machine, the combination with a fleshing cylinder mounted for rotation, and superposed feed rollers, of bell 90 crank levers supporting one of the feed rollers, a finger pivotally connected to one arm of each lever, means carried by said arm for yieldingly supporting the finger at a predetermined angle relative to the arm, yieldable means for supporting the finger carrying arms of the levers, and revoluble means operatively connected to the fingers for operating the bell crank levers and shifting the feed roller thereon toward and from the 100 fleshing cylinder.

In testimony that I claim the foregoing as my own, I have hereto affixed my signature in the presence of two witnesses.

ALBERTUS TRAVIS.
